his Attorney.

UNITED STATES PATENT OFFICE.

ARTHUR H. SCHAUM, OF ST. LOUIS, MISSOURI.

CLOSURE FOR HAND-HOLES.

1,194,080.

Specification of Letters Patent.

Patented Aug. 8, 1916.

Application filed May 13, 1915. Serial No. 27,745.

To all whom it may concern:

Be it known that I, ARTHUR H. SCHAUM, a citizen of the United States, residing at the city of St. Louis, State of Missouri, have invented certain new and useful Improvements in Closures for Hand-Holes, of which the following is a specification.

This invention relates to hand-hole plates and more particularly to means for securing hand-hole plates in position to close a hand-hole, and has for its object to provide a simple, cheap, and effective hand-hole plate adapted to be secured in position without the use of nuts, screws, or the like objectionable devices.

A further object of the present invention is to provide a simple device of the character described that may easily be secured in closed position in relation to a hand-hole and that may, also, be readily and quickly removed from closing position.

Moreover, the present invention consists in the combination and arrangement of parts more particularly described in this specification and set forth in the claim.

In the accompanying drawings forming part of this specification wherein like numbers of reference denote like parts wherever they occur, Figure 1 is a plan view of a hand-hole plate embodying the present invention associated with a fragment of a boiler or the like, showing the fastening means in place securing said plate in position for closing a hand-hole; Fig. 2 is a vertical cross sectional view of Fig. 1 showing a side plan view of the key driven home in a position securing the hand-hole plate in place, and showing, also, said key in dotted lines in a position partially removed from locking or wedging position. Fig. 3 is a view partly in cross section substantially at a right-angle to the cross section Fig. 2, and partly in plan showing a side elevation of the body-portion of the hand-hole plate and the outwardly extending slotted lug borne thereby with their associated parts depicted in cross-section; Fig. 4 is a cross-section on the line 4—4, Fig. 2, of the key; and Fig. 5 is a cross-section on the line 5—5, Fig. 2, of the key.

Plate 1 being the inner closure plate may be constructed of any suitable material and its lateral face 2 may outline a figure of substantially the shape and size of hand-hole 3 in boiler-plate 4 or the like, so that said plate 1 may substantially register in

the opening of said hand-hole, the height of said lateral face 2 being appreciably less than the thickness of said boiler-plate adjacent said hand-hole, as shown in the drawings, said plate 1 being constructed with a lateral extension or flanged portion 5 extending beyond said face 2 to provide a seat for mounting thereon gasket 6 or the like between said extension and the inner wall of said boiler-plate 4 or the like adjacent the edge of said hand-hole. Plate 1 is provided with an outwardly extending lug 7 borne substantially centrally of said plate and being adapted to extend outwardly therefrom through said hand-hole and beyond cover-plate 8, said cover-plate being adapted to cover said hand-hole and being adapted, also, to have a portion adjacent its outer edge rest upon or overlap the outer wall of a portion of said boiler-plate or the like adjacent the edges of said hand-hole, as best seen in Figs. 2 and 3, said cover-plate being provided with a substantially centrally located opening 9 therein adapted to permit said lug 7 to protrude therethrough, as shown in the drawings, the protruding end-portion of said lug being provided with a hole 10, which may be substantially triangular in shape as best seen in Fig. 3, said hole 10 being adapted to receive key 11 therethrough, said key being preferably curved and tapered as best seen in Fig. 2, and being, also, substantially triangular in cross-section as shown in Figs. 4 and 5, the curve of said key being such that each end thereof will be turned away from the outer surface of cover-plate 8 when said parts are in place, as best seen in Fig. 2.

Flanged extension 5 and lug 7 may be constructed integrally with plate 1, and the height of lateral face 2 of said plate 1 above said flanged portion being, as hereinabove described, appreciably less than the thickness of boiler-plate 4 or the like adjacent hand-hole 3, the forward surface of said plate 1 will not come in contact with the inner surface of cover-plate 8 when said parts and the parts associated therewith are in place with gasket 6 in position and key 11 in locking engagement, as best seen in Figs. 2 and 3, thus providing that said plate 1, flanged portion 5, and gasket 6 will constantly be under the force of the forward pull of said tapered key 11 in said locking position, and thus providing that key 11 bearing upon the outer

surface of cover-plate 8 will constantly cause the surface adjacent the outer edge of said cover-plate overlapping a portion of the material adjacent the edge of said hand-hole 6 to bear firmly against said overlapped portion to hold all parts of this device operatively in place in closing position.

Opening 10 is so disposed in the forward end-portion of lug 7 that the base of the 10 triangle outlining the shape of said opening will lie substantially parallel to the plane of the faces of cover-plate 8 when said cover-plate is in closing position, as shown in the drawings, and the apex of said triangle will 15 be turned toward the outwardly extending terminal of said lug, thus providing that when key 11 is inserted into said opening, the base-portion formed by the triangular shape of said key adapted to enter said triangular 20 opening, will be turned toward the adjacent outer face of said cover-plate. Key 11, being tapered from its larger end adjacent head 12 to its opposite terminal, forms a wedge which may be advanced into 25 said triangular opening sufficiently far toward said head 12 to draw plate 1 forwardly and to push cover-plate 8 firmly against the material adjacent hand-hole 3 to form a substantially fluid-tight joint between flanged 30 portion 5 and the adjacent portion surrounding said hand-hole, by means of pressing resilient gasket 6 or the like tightly between said flanged portion and said adjacent portion surrounding said hand-hole, said key 35 being curved along its length so that said base-portion thereof presents a convex curve along the length of said key to the adjacent outer surface of said cover-plate, so that, as said key is longitudinally advanced in said

opening 10, a portion of the surface of said base outlined by said convex curve slidably 40 engages a portion of the outer face of said cover-plate adjacent the edge of opening 9 in said cover-plate, and, also, the apex-portion of the triangular cross-sectional shape 45 of said key is slidably in engagement with the adjacent apex-portion of said triangular opening 10, as shown in the drawings.

I claim:

In a hand hole closure, the combination 50 of an inner plate of like outline as the hand hole and fitting easily therein with a peripheral flange to bear on the inner wall of a boiler, a central outwardly-projecting lug on the plate protruding through the hand hole 55 and having a triangular, slightly tapering opening therethrough, an outer cover plate adapted to bear on the external wall of a boiler over the hand hole and having a central aperture therein for said lug to pass 60 freely, one side of said triangular opening in the lug being within the aperture back of the outer side of the cover plate, and a curved wedge-key of triangular cross section tapering from end to end, adapted to be 65 driven into the triangular opening in said lug with its convex side toward the cover plate and bearing thereagainst immediately adjacent the aperture only, while the other two sides and the rounded angle of the 70 wedge between are forced into contact with similar sides and angle of the opening in the lug to hold the wedge immovable by frictional engagement of the said parts.

In testimony whereof I hereunto affix my 75 signature.

ARTHUR H. SCHAUML
